CLAIM

The ornamental design for an electronic camera, as shown and described.

DESCRIPTION

FIG. 1 is a front perspective view of an electronic camera showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing of the remainder of the electronic camera and its base represent disclaimed environmental structure and forms no part of the claimed design.
